ABSTRACT

An apparatus for recording characters, such as code characters, upon a magnetizable carrier which includes transmission wheels coupling setting members with character wheels having teeth provided with individual characters. An actuator is manually operated to align selected characters. The magnetizable carrier is moved by an arm operated by the actuator to bring it in contact with the aligned characters.

**APPARATUS FOR RECORDING CHARACTERS,
PREFERABLY CODE CHARACTERS ON A
CARRIER**

This invention relates to an apparatus adapted to record characters, preferably code characters, on a magnetizable carrier, comprising setting members accessible from outside which via transmissions coact with adjustable code character wheels actuatable by a magnetic circuit and consisting of a plurality of rotatable discs of magnetic material, which discs are of toothed wheel design with each tooth top forming a separate code character.

The invention has as its object to obtain a product, which on the basis of known constructions is cheap to manufacture and ensures that the information recorded on the magnetizable carrier by means of the code wheel is both intense and linear.

This object is achieved according to the invention in that the code wheels are arranged stationary and supported on an axle consisting of a permanent magnet with constant flow, that means are provided which upon actuation of the drive means in a first step forcibly linearize set code characters, and means which in a subsequent step forcibly move the magnetizable carrier into contact with the surfaces of the set code characters of the wheels.

At a suitable embodiment of the apparatus according to the invention, at which the code wheels are discs formed like toothed wheels of a magnetic material, with stationary spacer discs of non-magnetic material mounted therebetween, transmission wheels indirectly actuatable by the setting members mesh with the tooth gaps of the code wheels.

According to a further characterizing feature, the transmission wheels are tooth-shaped discs corresponding in number at least to the number of code characters and arranged in about the same horizontal plane as the code character wheels. For making the recording on the carrier apparent, the code character wheels comprise surfaces carrying code characters. The number of said surfaces exceeds the number of setting members, and the excess code character is marked the end of a recorded information and, respectively, the beginning of the subsequent recording. When the magnetizable carrier is of conventional magnetic tape, which is of relatively small width, it is essential for a subsequent undisturbed reading that the recorded characters are not offset relative to each other, but are located substantially in the same horizontal plane. This is achieved by means of an arm extending transversely to the code character wheel and supported on both sides, which arm upon actuation of the drive means forcibly enters between the tooth gaps of the code character wheel and entirely linearizes its tooth tops thereby rendering possible an undisturbed subsequent reading-off of the carrier.

Other characterizing features of the invention become evident from the following description of an embodiment, reference being made therein to the accompanying drawings, in which

FIG. 1 shows in a perspective way a portion of the front side of a recording apparatus comprising the device according to the invention.

FIG. 2 shows code character wheels and transmission wheels coacting therewith and the magnetizable carrier in a different view.

FIG. 3 is a section substantially along the line III — III in FIG. 1.

OPERATION IN GENERAL

5 In FIGS. 1 and 3, the reference number 10 designates the casing of a recording apparatus, for example a cash-register or any other apparatus with recording function. In the embodiment shown, a plurality of setting members 11 are movable along a curved line (FIG. 3). Each 10 of said setting members 11 actuates upon readjustment transmission wheels 12 and 13 coacting with each other and disposed on axles 14 and, respectively, 15. The axle 15 is a telescopic axle (FIG. 3) and connected at one end to transmission wheels 16, which according to 15 a known technique comprise a plurality of tightly adjacent toothed wheels 16'. The object of these wheels is to transmit the information determined by the setting members 11 to code character wheels 17 disposed in substantially the same horizontal plane. Each separate 20 toothed wheel coacts in a manner known per se with a definite setting member 11. The code character wheel in its turn is intended to transmit transactions made by means of the setting members 11 to a magnetizable carrier 18 (FIG. 2), for example in the form of a magnetic 25 tape adapted to be wound up on coils 18'. In the embodiment shown, the drive means is an arm 19 supported on an axle 30 (FIG. 3). Upon actuation of said arm the recording cycle will take place in the manner as described below in greater detail in conjunction with 30 a more detailed report on the elements comprised in the apparatus and being the subject matter of this invention.

CODE CHARACTER WHEEL

35 The code character wheel generally designated by 17 comprises a plurality of rotatable discs 17' of magnetizable material. The discs are designed like toothed wheels, each tooth top forming a separate code character. The code character discs are spaced apart by stationary, preferably non-magnetizable discs 19 (FIG. 2). Said code character discs, comprising the separately 40 rotatable discs 17' as well as the spacer discs 19, are disposed on a stationary central axle 20, which consists of or is connected to a permanent magnet delivering a constant flow. This flow is distributed uniformly over the code wheel, as the axle 20 forms a central suspension means, i.e. the separate toothed discs are disposed 45 concentrically on said axle 20. The number of tooth tops carrying code characters is chosen according to the desired different recording types, and the number of separate code character toothed wheels exceeds the number of setting members. The excess code character disc or discs are thereby utilized to mark the end of a completed recording cycle and, respectively, the beginning 50 of the subsequent recording. The separate toothed discs of the transmission wheels are adapted to coact one by one with the tooth gaps of preceding code character wheels, and the code character wheels and transmission wheels lie substantially in the same horizontal 55 plane. thereby

60 The function of the apparatus described becomes evident from FIG. 3 and can be described as follows:

The setting members having been actuated in the desired way, the code wheels 17 have been actuated in the manner described and thereby have been set. Upon actuation of the drive means 31, which is mounted rigidly on the axle 30, in a first phase a cam wheel 21 dis-

posed on the axle 30 will actuate one end of a yoke having two parallel arms 22, 23 (FIG. 1), which at the other end are connected by an arm 24 so adapted and located, that it drops into the tooth gaps of the code wheel and forcibly causes the individual toothed wheels to assume a practically entirely linear direction. This implies that all tooth tops will be aligned with each other. Upon the continued actuation of the drive means, in a second phase a further cam wheel 25 mounted on the axle 30 will be caused to actuate one end of a spring-loaded arm 26, the other end of which engages with the casing of the magnetizable carrier 18 and lifts up the carrier 18 into contact with the linerized code characters on the code wheel.

We claim:

1. Apparatus for recording characters, such as code characters, on a magnetizable carrier, comprising a series of manually operable setting members for selecting characters to be recorded on said carrier and arranged side by side, a series of independently rotatable toothed character wheels of a magnetizable material arranged side by side, an individual character being arranged upon the top of each tooth, movement transmission

wheels mechanically coupling each setting member with a corresponding character wheel for setting the selected character tooth in a ready-to-record position relative to said carrier, a permanent magnet shaft with 5 a constant magnetic flow rotatably supporting said character wheels, a common manually operable actuator, means comprising an aligning rod cooperating with the tooth gaps of said character wheels and operable upon actuation of said actuator to align all selected 10 characters of the character wheels mutually as well as in relation to said carrier, and means operable upon further actuation of the actuator to move said carrier into contact with said aligned characters.

2. Apparatus according to claim 1, further comprising spacer discs of a non-magnetic material between 15 the individual character wheels and transmission wheels having teeth meshing with the tooth gaps of said character wheels.

3. Apparatus according to claim 1, wherein the number 20 of character wheels exceeds the number of setting members, the excess wheels being used for marking the end and the beginning of a recorded information.
